UNITED STATES PATENT OFFICE.

WILLIAM A. SCOTT, OF TACOMA, WASHINGTON.

MEANS FOR ATTACHING BINDING-POSTS TO DRY BATTERIES.

1,021,340.

Specification of Letters Patent. Patented Mar. 26, 1912.

Application filed October 14, 1911. Serial No. 654,779.

To all whom it may concern:

Be it known that I, WILLIAM A. SCOTT, a citizen of the United States, residing at Tacoma, in the county of Pierce and State of Washington, have invented certain new and useful Improvements in Means for Attaching Binding-Posts to Dry Batteries; and I do hereby declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to certain new and useful improvements in means for attaching binding posts to dry batteries.

The invention has for its object the provision of a simple and efficient means for securing a binding post to the sheet metal edge of a dry battery in such manner as to prevent its accidental displacement or its being torn loose from its connection by the tightening of the binding screw, which so frequently happens by the ordinary method of securing the post by solder alone.

To this end and to such others as the invention may pertain, the same consists in the novel construction and in the peculiar arrangement, combination and adaptation of parts, all as will be more fully herein-after described, shown in the accompanying drawing and then specifically defined in the appended claim.

The invention is clearly illustrated in the accompanying drawings which, with the letters of reference marked thereon, form a part of this specification and in which:—

Figure 1 is a perspective view of a portion of the upper end of a dry battery casing with my device applied thereto. Fig. 2 is an enlarged perspective view of the binding post detached. Fig. 3 is a central vertical section taken through the binding post attached, and Fig. 4 is an enlarged detail in perspective showing the locking flange which receives the upper edge of the casing to which the post is attached.

Reference now being had to the details of the drawings by letter, A represents a dry battery casing of ordinary construction and B my improved post attached thereto. The post B has its lower portion bifurcated and leading from the inner wall of the bifurcation upon one side thereof is a curved recess C. Above the bifurcated lower portion of the binding post the usual shoulder D and screw-threaded extension or post E is provided and the wire, when connected with the post, is seated upon the shoulder D and clamped between said shoulder and the lower edge of the binding screw E as is common in attaching wires to battery cases.

In attaching the post to the edge of the battery case, the slotted lower end of the post is fitted over the upper edge of the casing to which it is to be attached and, by one or two blows imparted by a hammer to the upper screw-threaded end of the post, the upper edge of the casing is cut away and caused to enter the recess C and is bent or clamped within the recess, thus securing the post to the casing. If desired, the post, when thus clamped in position to the edge of the casing, may be reinforced by use of solder as will be readily understood.

Having thus fully described my invention, what I claim to be new and desire to secure by Letters Patent is:—

In combination with a wall of the casing having a portion of its marginal edge bent to form a laterally extending and curved portion, a binding post having a shank portion with a longitudinal head formed in its lower end and terminating in its inner end in a widened portion, the marginal outline of which is concaved to conform to the said curved portion, which is adapted to engage the inner end of the recess, as set forth.

In testimony whereof I hereunto affix my signature in the presence of two witnesses.

WILLIAM A. SCOTT.
